UNITED STATES PATENT OFFICE.

HENRY F. ROONEY, OF RANDOLPH, MASSACHUSETTS, ASSIGNOR TO MELLEN
BRAY, TRUSTEE, OF NEWTON, MASSACHUSETTS.

CUSHION-TREAD FOR HEELS, &c.

SPECIFICATION forming part of Letters Patent No. 718,526, dated January 13, 1903.

Application filed January 15, 1902. Serial No. 89,817. (No model.)

To all whom it may concern:

Be it known that I, HENRY F. ROONEY, of Randolph, in the county of Norfolk and State of Massachusetts, have invented certain new and useful Improvements in Cushioned Treads for Heels, &c., of which the following is a specification.

This invention relates to elastic treads, principally for boot and shoe heels, although it may be embodied in a tread for use on other articles.

The invention has for its object, first, to provide an elastic tread with metallic wear-pieces forming parts of the tread-surface and adapted to reduce to the minimum the wear of the elastic body of the tread, said wear-pieces including also nail-engaging washers forming parts of or attached to said wear-pieces and yieldingly supported at their upper sides by portions of the elastic material of the tread, so that the wear-pieces shall not only prolong the durability of the elastic body of the tread without materially interfering with the resilience of the latter, but shall also provide for the attachment of the tread to a heel or other article by means of attaching-nails.

The invention consists in the improvements which I will now proceed to describe and claim.

Of the accompanying drawings, forming a part of this specification, Figure 1 represents a bottom view of an elastic heel-tread embodying my invention. Fig. 2 represents a section on line 2 2 of Fig. 1. Fig. 3 represents an enlargement of a portion of Fig. 2, showing in dotted lines a portion of an attaching-nail engaged with the tread. Figs. 4 and 5 represent perspective views of different forms of combined wear-piece and nail-engaging washer. Fig. 6 represents a sectional view of the form of wear-piece and washer shown in Fig. 5. Fig. 7 represents a perspective view of a vulcanizing-mold suitable for use in the manufacture of the elastic tread shown in Figs. 1 and 2.

The same reference characters indicate the same parts in all the figures.

In the drawings, *a* represents the elastic

body of my improved tread, the same being 50 in this case formed for application to a boot or shoe or to the heel thereof.

b represents a series of metallic wear-pieces which are embedded in the body *a*, their outer ends being flush with the tread-surface of said 55 body, while their inner ends are below the upper surface of the body. The outer ends of the wear-pieces therefore form parts of the tread-surface and reduce to the minimum the wear of the elastic body by contact with the 60 ground. The inner ends of the wear-pieces being separated, as above stated, from the upper surface of the body *a* are backed by portions of said elastic body, so that they yield with the elastic body, and therefore do not interfere materially with the cushioning effect. 65

I prefer to make the wear-pieces *b* tubular in form and to form the inner end of each wear-piece so that it is adapted to serve as a washer for engagement with one of the nails 70 *c*, which attach the tread to a boot or shoe. To this end I form a head *b'* on the inner end of the tubular body of the wear-piece *b*, said head being preferably disk-shaped and provided with a central perforation *b*², which 75 coincides with the interior of the tubular body and is of smaller diameter, so that a flange, shoulder, or seat is formed at the inner end of the wear-piece *b* for engagement with the head *c'* of the attaching-nail, as clearly 80 shown in Fig. 3. The tubular body of the wear-piece is of sufficient diameter to receive the head *c'*, so that the said tubular body may be termed a "nail-cup."

The outer end of the tubular wear-piece *b* 85 may have an outwardly-projecting flange *b*³ to increase the area of wear-resisting surface. Said flange may be star-shaped, as shown in Figs. 1 and 4, this shape imparting an ornamental appearance to the tread-face of the 90 body *a*. If desired, however, the flange *b*³ may be omitted, as shown in Figs. 5 and 6.

The described tread may be made by mounting the tubular wear-pieces *b* upon fixed pins *d*, projecting into the cavity of a vulcanizing-mold *e*, then filling said cavity with elastic unvulcanized rubber or rubber composition and suitably closing or covering the cavity 95

and then vulcanizing the rubber in the usual manner.

I claim—

1. A tread for heels, &c., comprising an elastic body, and independent metallic wear-pieces embedded in the said body with their outer ends substantially flush with the tread-surface, their inner ends being formed as nail-engaging washers which are located below the upper surface of the body and have nail-head seats surrounded by the tubular portions of the wear-pieces, the said wear-pieces being yieldingly supported by the portions of the elastic body between the washers and the upper surface of the body.

2. A tread for heels, &c., comprising an elastic body and tubular metallic wear-pieces embedded in the said body and having outwardly-projecting wear-flanges at their outer ends which cover portions of the body, and heads at their inner ends constituting nail-engaging washers, said heads being located below the upper surface of the body.

In testimony whereof I have affixed my signature in presence of two witnesses.

HENRY F. ROONEY.
